DESIGN FOR A BUS HEATER OR SIMILAR ARTICLE

Peter J. Miller, Detroit, Mich., assignor to Evans Products Company, Detroit, Mich., a corporation of Delaware

Application May 22, 1940, Serial No. 92,521

Term of patent 7 years

To all whom it may concern:

Be it known that I, Peter J. Miller, a citizen of the United States, residing at Detroit, in the county of Wayne and State of Michigan, have invented a new, original, and ornamental Design for a Bus Heater or Similar Article, of which the following is a specification, reference being had to the accompanying drawing, forming part thereof, in which: the figure is a perspective view of a bus heater, or similar article, showing my new design.

The side and end of the heater not shown in the drawing are substantially plain.

I claim:

The ornamental design for a bus heater or similar article, substantially as shown and described.

PETER J. MILLER.
